ANTON C. MENGE, OF NEW ORLEANS, LOUISIANA

FILTER

Application filed November 13, 1929. Serial No. 406,924.

The object of this invention is to provide a simple, inexpensive and efficient mechanism whereby water may be filtered automatically as it is drawn from a supply for use. The 5 invention provides a series of cells containing filtering material through which the water successively rises, overflowing from the top cell of the series and collecting in an outer casing from which it is drawn for use. 10 The invention is illustrated in the accompanying drawing and consists in certain novel features which will be hereinafter first fully described and then particularly defined in the appended claim.

15 In the drawing: Figure 1 is a vertical section of a filter embodying the present invention, and Fig. 2 is a detail plan view of one of the partitions which separate adjoining cells.

20 In carrying out the invention, there is provided an outer casing 1 which may be of any suitable or preferred dimensions and is provided with a removable cap plate or upper head 2 from which there rises centrally a vent tube 3. Upon one side of the casing is a gage tube 4 through which the height of the water in the casing may be easily noted, this tube being of glass and being in communication with the casing at the top and bottom of the 25 same, as shown and as will be understood. In the bottom of the casing is a drain plug 5 to facilitate cleaning when necessary and also at the bottom is a draw-off faucet 6 which may be of any approved type.

30 35 Disposed within the casing and in spaced relation thereto is an inner shell 7 preferably of cylindrical formation and of some durable material which will withstand dampness. This inner shell is supported within the casing by brackets or feet 8 which are secured to the lower end of the shell and to the bottom of the outer casing so as to support the shell above the bottom. Within the shell a plurality of brackets or lugs 9 are 40 provided thereon, said brackets being arranged in series extending the entire height of the shell, as shown, and being intended to support perforated partitions or disks 10 which are provided in their peripheries with notches 11 whereby each disk may be slipped 45 past upper brackets to reach the brackets upon which it is to rest and then by being turned so as to bring the notches out of alignment with the brackets to rest upon the brackets in an obvious manner. These disks are 55 provided with openings 12 therethrough so that the water may pass through the disks from one cell to a succeeding cell. Upon reference to Fig. 1, it will be noted that the disks are supported by the brackets in spaced 60 relation and they, therefore, define a plurality of cells within the shell which are adapted to contain filtering material. The lowermost cell or the space below the lowest disk 10 is left empty so that the water may 65 accumulate therein, as will be understood, the force of the water being thereby reduced so that it will not flow through the openings 12 in the lowest disk with sufficient velocity to disturb the filtering material which is disposed above said disk. While any suitable filtering material may be employed, I prefer to use and have indicated lumps of charcoal 13 in the first and third cells counting upwardly while the second and fourth cells 70 contain sponges 14. At the top of the shell, there is provided an additional disk 15 which is the same in all respects as the disks 10, except that the notches 11 may be omitted, 75 said disk 15 resting directly on the sponges 80 on the top cell and being adapted to compress said sponges so that the flow of water through the same will be effectually retarded and any foreign matter in the water will be removed 85 therefrom in an efficient manner. A dome-shaped perforated cap 16 is secured upon the upper end of the shell 7 and mounted centrally in said cap is a pressure screw 17 which bears upon the disk 15 so that if the 90 pressure screw be turned home said disk 15 will be caused to compress the uppermost sponges 14 in the manner previously mentioned. In the upper end portion of the outer casing between the cap plate 16 and the head 2 of the casing is arranged a float 18 from 95 which a needle valve stem 19 rises to play within the vent tube 3. As the level of water within the casing 1 rises, the float will be raised and the valve stem 19 will engage the exit opening 20 in the vent tube so as to cut 100

off ingress of air and thereby prevent pressure being exerted upon the water which might cause leakage.

The water is supplied to the filter and the outer casing 1 from a reservoir or tank 21 which may be supported in any convenient manner at a point remote from the filter but above the level of the same so that the water will flow by gravity from the reservoir to the filter. A pipe 22 leads downwardly from the bottom of the reservoir and has its lower end upturned to pass through the bottom of the casing 1 and be secured in the bottom of the inner shell 7 to establish communication with the interior of the shell. Cut-off valves 23 of any approved form are provided in the pipe 22 at convenient points so that the flow of the water may be easily controlled. The water flowing from the reservoir will pass upwardly into the shell 7 and the weight of the volume of water in the pipe 22 and the pressure exerted thereon by the body of water in the reservoir will cause an upward flow through the several cells of the filter so that the impurities will be removed and the clear water may escape through the perforations of the cap 16 and overflow into the outer shell. The level of the water in the shell will be indicated in the gage tube 4 and the flow may be cut off or established as may be necessary to maintain the water at such level as experience may indicate to be advisable. The water is drawn off for use through the faucet 6 and, of course, the level of the water in the outer casing will drop as water is drawn off. The float 18 and valve 19 will rise and fall with the level of the water at the top of the casing and the exit opening 20 will, consequently, be opened or closed so that whenever the casing is about full inflow of air will be arrested and when the level drops air may be admitted so that a vacuum will not be established to interfere with the circulation of the water while at the same time there will be no trapping of air to prevent free flow of the water from the filter cells. The device is exceedingly simple in the construction and arrangement of its parts and will operate entirely automatically. After being once set up, no further adjustment is necessary and the device will operate for a long period without requiring any attention.

Having thus described the invention, I claim:—

55 A filter comprising an outer cylindrical casing, an inner shell mounted concentrically within the casing and spaced throughout therefrom, a liquid inlet rising through the bottom of the casing and passing into the bottom of the shell, a series of perforated disks supported within the shell, filtering media between the disks, the uppermost disk resting directly on and being supported solely by the uppermost filtering medium, a perforated cap at the upper end of the shell

through which liquid may overflow into the casing, a pressure screw mounted in said cap and bearing on the uppermost disk a vent tube rising from the top of the casing, a float in the casing in alignment with said screw, a valve stem rising from said float and playing in said vent tube and adapted to open and close the exit thereof, the float being disposed over the pressure screw whereby it may rest thereon to limit the opening movement of the valve, and a draw-off device at the lower end of the casing.

In testimony whereof I affix my signature.
